(57) **CLAIM**

The ornamental design for a current transducer, as shown and described.

DESCRIPTION

1. Current transducer

1.1 : Perspective

1.2 : Perspective

1.3 : Front

1.4 : Back

1.5 : Top

1.6 : Bottom

1.7 : Left

1.8 : Right

The circles and ovals visible at the left and right ends in views 1.5 to 1.6 are see-through holes.

Broken lines included in the drawings show unclaimed portions of the design.
